UNITED STATES PATENT OFFICE.

DRURY D. BAILEY AND JAMES O. BAILEY, OF BANNER, CALIFORNIA.

ROCK BREAKER AND PULVERIZER.

SPECIFICATION forming part of Letters Patent No. 752,945, dated February 23, 1904.

Application filed June 15, 1903. Serial No. 161,553. (No model.)

To all whom it may concern:

Be it known that we, DRURY D. BAILEY and JAMES O. BAILEY, citizens of the United States, residing at Banner, county of San Diego, State 5 of California, have invented an Improvement in Rock Breakers and Pulverizers; and we hereby declare the following to be a full, clear, and exact description of the same.

Our invention relates to an apparatus which 10 is designed for breaking and pulverizing rock and in conjunction therewith of a feed and sampling device.

It consists of a double cone vertical spindle turnable in a shell of such shape that the upper portion of the spindle, in conjunction with the cylindrical or opposed portion of the shell, first breaks the rock to comparative fineness, and the remaining portion of the shell, converging with relation to the convergent lower 15 part of the spindle, completes the crushing. By suitable adjustments of the spindle with relation to the shell any degree of fineness may be obtained. Suitable feed and discharge 20 connections and adjustments are employed in connection with the apparatus.

Referring to the accompanying drawing, the figure represents a vertical sectional view, partially in elevation, of a rock breaker and pulverizer embodying our invention.

It is the object of our invention to provide 30 an apparatus into which the rock from the ore-bin may be transferred through a feeding and sampling device, the rock being first broken or crushed to a certain degree of fineness in 35 the upper part of the apparatus and the pulverizing to any degree of fineness being completed in the lower portion.

As shown in the drawings, A is the substantially cylindrical upper portion of the 40 shell, the lower part A' of which is convergent from the bottom of the cylindrical portion to its lower end. This shell is made of suitable material and having strength enough to resist the outward pressure while the crushing is 45 going on. It is here shown as being supported upon foundation-plates, as at 2, these plates resting upon suitable supporting-timbers, not here shown.

3 is a solid revoluble spindle the upper portion of which lies within the cylindrical por-

tion A of the shell. The lower portion 3^a lies within the lower convergent portion of the shell. This spindle is made as shown, the upper portion diverging downwardly within the shell to its junction with the lower portion 55 3^a, and this forms the largest diameter of the spindle. From this junction the spindle converges within the convergent portion A' of the shell, the convergence of the spindle being less than that of the shell. The extreme 60 lower end of the spindle very nearly fills the lower end of the shell, so that during its revolution the rock or material to be crushed gradually passes down within this convergent channel and is reduced to as fine a degree as may 65 be desired. The spindle may be made in one or more pieces. If made in two pieces, it may be joined in any suitable manner at the junction-line between the two conical portions 3 3^a or at any other desired point, so that any portion which is subjected to the greatest amount 70 of wear may be replaced whenever wear makes it necessary. This crushing-cone has an extension or spindle 4 at the lower end, and this is fitted and turnable in a step 75 5. The step may be supported upon a suitable base or plate, as at 6, and this plate or base may be adjusted either by screws 7, passing through an outwardly-turned flange 8 at the bottom of the shell A', or in any other suitable and 80 well-known manner. By this adjustment the cone 3^a may be raised or lowered with relation to the shell, and the convergent channel between it and the shell may be enlarged or diminished to suit any degree of fineness to 85 which it may be desired to reduce the material.

9 is a tripod or support of any suitable description. The upper central portion of this tripod is provided with a bearing 10, and the 90 upper portion of the cone 3, which may be made substantially cylindrical, enters and is guided within this bearing.

11 is a cap fitted and movable within the bearing 10, and it is shown with its lower face 95 made concave and fitting the corresponding convexity of the upper end of the cone 3, as shown at 12.

In the upper part of the bearing 10 is a fixed nut 13, through which passes a regulating-

screw 14, the lower end of which bears upon the cap 11, and by means of this screw and the regulating-screws 7 at the bottom the double cone may be raised or lowered and properly guided in its revolutions. Power may be applied to revolve this cone through pulley, gearing, or other equivalent device, as shown at 15.

Surrounding the step 5 is a discharge-chute 16, so disposed that the pulverized material from the space between the cone 3^a and the shell A' will be delivered into this chute. The step 5 may be tapered or converged toward the top so as to leave as little surface as possible at its upper end, and it may be further protected by a sleeve or cap 17, made convex on the upper surface so that any material falling upon it will be delivered clear of the step and will not be allowed to enter, thus protecting the step and spindle 4 from undue wear.

Any suitable form of collar or protecting device may be substituted for that herein described, the object being in any event as far as possible to keep the dust and grit out of the step.

In order to feed the ore or rock to be crushed, we have shown an inclined cylinder 18, mounted and turnable upon bearings, as at 19, and power may be applied by belt or gearing in any suitable or well-known manner to revolve the cylinder. The upper end of the cylinder is reduced in diameter or has a head with a central opening, as at 20, and into this opening the chute from the ore-bin 21 is adapted to deliver the material, and the revolution of the tube 18 will cause it to gradually travel down the incline. The lower end of the cylinder extends into the upper portion of the shell A, so that the rock is delivered between the cylindrical portion of the shell and the divergent upper cone 3. The revolution of this cone carries the rock gradually down between itself and the cylindrical portion A, and it is continually reduced in size until it passes the junction between the two cones, then it is further reduced in size as it passes down in the convergent channel between the lower cone and the lower conical portion of the shell until it is reduced to its finest condition at the point of discharge. It will be seen that the tendency of the rock-pressure between the upper cone and the cylinder will be to press the crusher down and prevent it from being forced up, this portion of the cone counteracting any upward pressure which may take place between the lower convergent portion of the cone and the corresponding convergent portion of the shell, and this in addition to the adjusting-screws 7 and 14 enables the operator to regulate the position of the crusher with great nicety and without any undue strain or pressure upon the parts.

In order to determine the character of the rock which is being delivered to the crusher, we have shown an opening 22 in the side of

the revoluble feed-chute 18, and this is of such size that at each revolution of the chute a small portion of the passing material will be discharged and may be employed as a sample.

Having thus described our invention, what we claim, and desire to secure by Letters Patent, is—

1. A crusher and pulverizer consisting of a shell, the upper portion of which is cylindrical, the lower portion convergent, a crusher 75 consisting of an upper cone divergent downwardly and a lower cone convergent downwardly, the bases of said cones being contiguous, a feed-chute connecting with the cylindrical portion of the shell at a point below the 80 top thereof, a step and a spindle forming a journal for the lower cone, and a cap within which the upper end of the upper cone is turnable, and screws by which the step and cap are vertically adjustable.

2. The combination in a crusher of a stationary shell comprising a cylindrical upper and a convergent lower portion, a crusher axially turnable within the shell consisting of an upper portion divergent downwardly and a 90 lower portion convergent downwardly, the bases of the two parts being united, a spindle projecting from the lower cone and a step in which it is supported and turnable, a support having a bearing within which the upper end 95 of the crusher projects, a cap and a screw by which said cap is movable within the bearing, said cap having a concaved socket in which the correspondingly - shaped head of the crusher is revoluble, a chute inclosing the 100 spindle and adapted to receive the discharged material, and means protecting the step and preventing the entry of pulverized material.

3. The combination in a crushing and pulverizing apparatus of a double cone, the upper part divergent and the lower part convergent downwardly, an adjustable step and guide at the bottom and top respectively, means by which the cones are revoluble on their bearings, a fixed exterior shell, the upper portion 110 being cylindrical and inclosing the divergent upper cone, the lower portion convergent and inclosing the lower convergent cone, a chute by which material to be crushed is delivered into the upper portion of the shell, a chute surrounding the step into which the pulverized material is delivered from the lower part of the crusher.

4. The combination in a crusher and pulverizer of the double revoluble cones with inclosing cylindro-conical stationary shell, and means for adjusting the cones within the shell to regulate the discharge at the lower end, a spindle and a step within which the spindle is supported, a chute inclosing the spindle adapted to receive the discharged material, and a protecting-cap carried by the spindle and projecting over the step to prevent the entry of the pulverized material.

5. The combination in a crushing and pul-

verizing apparatus, of a cone and shell, a revoluble inclined chute connecting the ore-bin and the upper part of the shell said chute having a supplemental discharge-opening at one side, and a chute into which the pulverized ore is delivered from the bottom of the apparatus.

In witness whereof we have hereunto set our hands.

DRURY D. BAILEY.
JAMES O. BAILEY.
